UNITED STATES PATENT OFFICE.

FRANK F. FORSHEE, OF FLINT, MICHIGAN, ASSIGNOR TO WESTINGHOUSE ELECTRIC
PRODUCTS COMPANY, A CORPORATION OF MICHIGAN.

SADIRON STAND.

Application filed October 29, 1920. Serial No. 420,448.

To all whom it may concern:

Be it known that I, FRANK F. FORSHEE, a citizen of the United States, and a resident of Flint, in the county of Genesee and State 5 of Michigan, have invented a new and useful Improvement in Sadiron Stands, of which the following is a specification.

My invention relates to electrically heated apparatus and particularly to electric flat 10 irons, and it has for its object to provide a relatively simple means for supporting a flat iron in a sidewise-tilted position.

In practicing my invention I provide a resilient member of substantially U-shape 15 secured to the top of the body of the iron and so bent as to extend a substantial distance therefrom and parallel thereto.

In the single sheet of drawings,

Figure 1 is a view, in side elevation with 20 certain portions shown in cross section, of a flat iron comprising the device embodying my invention.

Fig. 2 is a view, in rear elevation, of a flat iron when placed in its sidewise-tilted 25 position.

Fig. 3 is a perspective view of a supporting member and of its clamping means, and

Fig. 4 is a top plan view of a modification of a supporting member.

30 In the drawings, an electrically heated flat iron 1 comprises a bottom plate 2, a heating element 2^a, a top plate 3^a (if desired) a cover member 3 and a handle member 4, the handle member being secured 35 to the body of the iron as by strap members 5.

The electric heating element is located 40 between the bottom plate 2 and the top plate 3^a and is provided with suitable terminal members 6. A guard member 7 is provided to protect the terminal members 6 and also to act as a guide for a suitable connecting plug (not shown) when the same is pressed 45 on the terminal members 6 to permit of energizing the heating element.

A supporting member 8 comprises a single 50 piece of resilient material so bent as to be of substantially U-shape, with the inner end portions 9 of the piece of material located 55 relatively closer together than the outer ends of the side portions 10. The connecting portion 11 may be bowed upwardly, particularly when used on an iron having a handle substantially similar to that shown in 60 the drawing, although this is not essential.

The portions 10 are so bent as to bring the connecting portion 11 a substantial distance away from and parallel to, the side of the iron and at a small distance above the lower edge of the bottom plate 2.

60 The portions 9 are so bent as to extend laterally of the body of the iron and may be secured against the top or cover of the iron by a clamping member 12. The clamping member 12 is formed of a single piece 65 of sheet metal provided with a substantially circular opening 13 and with two upwardly and downwardly curved end portions 14, the under surface of each of which is adapted to hold one of the portions 9 against the upper 70 surface of the cover member 3. A bolt 15 holds the clamping member 12 against the cover member and also holds the top plate 3^a, the cover member 3, the heating element 2^a, and the bottom plate 2, in their proper 75 operative positions.

While I have shown a specific form of the 80 resilient supporting member 8, as well as a specific form of clamping member, I do not wish to be restricted thereto as I may so bend the end portions 9 as to permit them being directly clamped under the head of the bolt 15, a modification which is illustrated in Fig. 4. If the supporting member 8 is formed as shown in Fig. 3, it may 85 easily be removed from the iron if an operator desires to place it on the other side thereof, thus permitting of its use by a right handed or a left handed operator.

90 It may be noted that the device embodying my invention provides a simple means secured to the iron adapted to permit of resting the iron in a sidewise-tilted position on the ironing board or other surface. When in this sidewise-tilted position, the 95 iron is supported on three points, one of which is constituted by the middle of the intermediate and upwardly bowed portion 11, and the other two points are constituted by the end portions of the handle member 100 4. (See Fig. 2). It may also be noted that 105 it is relatively easy to so tilt the iron, as it is only necessary to first tilt the iron on the near edge of the bottom plate 2, and then on the connecting portion 11 of the supporting member, until the handle 4 rests upon the table. In case a removable supporting member is used it may be noted 110 that this will permit the iron being used by either a right handed or a left handed

operator, and of its being tilted by the operator into a corresponding right hand or left hand sidewise-tilted position.

Various modifications may be made in the device without departing from the spirit and scope of my invention, and I desire that only such limitations shall be placed thereon as may be imposed by the prior art or are specifically set forth in the appended 10 claims.

I claim as my invention:

1. The combination with an electric flat iron, having a cover member, of a laterally-extending supporting member comprising 15 two side portions, a connecting bottom portion, and two end portions spaced from each other and from the side portions, a

clamp for receiving the end portions; and a single bolt for securing the clamp and the cover member on the iron.

2. The combination with an electric flat iron having a horizontal handle, of a laterally-extending supporting member comprising a single piece of material bent to comprise two arms and an intermediate portion of bowed shape, the handle providing two points and the middle of the bowed intermediate portion providing the third point of a three-point support for said iron when in a sidewise tilted position.

In testimony whereof, I have heretunto subscribed my name this 25th day of Oct. 1920.

FRANK F. FORSHEE.
